UNITED STATES PATENT OFFICE.

OLIVER H. ARNO, OF WILMINGTON, ASSIGNOR TO THE AMERICAN AUTOMATIC ORGAN COMPANY, OF BOSTON, MASSACHUSETTS.

MECHANICAL MUSICAL INSTRUMENT.

SPECIFICATION forming part of Letters Patent No. 268,979, dated December 12, 1882.

Application filed March 15, 1882. (No model.)

To all whom it may concern:

Be it known that I, OLIVER H. ARNO, of Wilmington, in the county of Middlesex and State of Massachusetts, have invented certain new and useful Improvements in Mechanical Musical Instruments, of which the following is a full, clear, and exact description.

This invention relates to mechanical musical instruments wherein reeds or other sound devices to be sounded by the passage of air through them are permitted or automatically caused to sound in accordance with a perforated music sheet or strip—such as a sheet or strip of perforated paper—which is made to pass through the instrument, and as it so passes to secure the opening and closing, through mechanism, of valves to the reeds or other sound devices, the “organina,” so called, being a well-known instrument of this class.

The invention consists, first, in a mechanical musical instrument, of a cap or case arranged upon one side of the music-strip and provided with and carrying a reed-board, with its reed-chambers, each containing a reed, a valve to each reed-chamber, and separate mechanism for securing the opening and closing of each valve by and because of the passage of a perforated music-strip in proper relation therewith, all substantially as hereinafter described;

second, in a mechanical musical instrument, of reed-chambers having reeds and valves and levers for the opening and closing of the valves by and because of the passage of a music-sheet in proper relation therewith, in combination with a spring constructed and arranged to make the connection between each lever and its valve, all substantially as hereinafter described; third, in a mechanical musical instrument, of reed-chambers having reeds and

valves, in combination with levers arranged for opening and closing the valves and to so operate by and because of the passage of a music-sheet in proper relation therewith, and to exert an elastic and yielding pressure upon the valves in closing and holding them closed, and when operated for the valves to open to leave the valves free to move without obstruction or hinderance from the levers, all substantially as hereinafter described.

In the accompanying plate of drawings, Figure 1 is a central vertical section from the front

to the rear end of the instrument. Fig. 2 is in part elevation at the rear end and a transverse vertical section through one pair of the exhaust-bellows and the part of the instrument above 55 the bellows. Fig. 3 is a horizontal section on line 3 3, Fig. 1, for a part of the width of the instrument and a plan view for the remainder of the width, with some portions of the top board of the casing removed in substance, 60 those portions below the disconnected dotted line x x of Fig. 1 and the top of the flexibly-connected frame making a part of the race-way for the perforated music-strip; Figs. 4, 5, and 6, vertical sections, each illustrating 65 modifications, to be hereinafter particularly described.

In the drawings, A A represent the boards making the two sides, and B and C are boards, respectively, making the front and rear ends, 70 all of which are joined in any suitable manner, and together with a top board, D, make substantially the casing of the instrument.

E E are exhaust-bellows, four in number. These bellows are placed horizontally, two 75 above and two below a common horizontal board, F, which is secured to the side boards, A, and all have vertical air-passages a, leading from them to a horizontal air-passage, b, in the horizontal board F, which air-passage b opens 80 to a common vertical reservoir-bellows, H, that in its upper portion communicates with the lower end of an inclined vertical air-passage, e, having at its upper end a vertical mouth-piece, d, opening at and in a horizontal plane 85 coincident with the upper and flat surface, f, of the top board, D, of the casing. The exhaust-bellows E E are in pairs; and for those of each pair to operate alternately—that is, for the one to open while the other closes, and 90 vice versa—the bellows of each pair are connected together by a rod, g, and one of each pair is connected by a separate pitman-rod, h, to separate crank-arms l of a common horizontal shaft, L, which is located in the top 95 board, D, to turn within a groove, m, thereof in suitable bearings of the side boards, A, and to be driven by a crank-handle, M, outside of the casing.

The crank-shaft L, in its portion within the 100 groove m of the top board, constitutes the feed-roller N, and directly above it is a presser-

roller, O, hung at each end in suitable bearing-blocks, n, having a yielding pressure, all in a manner with the rotation of the feed-roller to feed the paper strip P along the upper surface of the top board, D, and otherwise through the instrument, as will hereinafter appear, and also to work the exhaust-bellows E, and through them the reservoir-bellows H, all of which bellows, except as herein particularly explained, are constructed and arranged for operation as usual.

The mouth-piece d, hereinbefore referred to, runs across the instrument, and it has a vertical slot or air-passage, o, of a length to embrace all the lines of perforations in the music-strip, and about and around it is located a horizontal frame, Q, which has a rectangular opening, p, of larger dimensions than the outer periphery of the mouth-piece.

20 The frame is connected by leather q or other suitable flexible material to the outside of the mouth-piece below its open end, which leather connection closes the space p between the frame and the mouth-piece.

25 The frame Q, flexibly connected to and situated about the mouth-piece, as above described, is within an opening, r, of the top board, D, and the music-strip, in passing through the instrument, moves over the surface of the frame Q and the open end of the mouth-piece d, and also the top board, D, and in passing over the frame Q and mouth-piece d it passes between them and the under side of the cap or case W, which is situated directly above.

30 35 The cap or case W carries the reed-board R, covers the frame Q and mouth-piece d, and in such position it is supported by a rest at each end upon cheek-blocks s of the top board, D, to which or to the side boards, A, it is secured, and obviously preferably by screws, so that it can be readily attached or detached.

The positions above described of the cap or case W and of the frame Q are such relatively as to secure close bearings of both parts upon the perforated paper strip in its passage between them. The cap or case W has an inside chamber or wind-chest, S, that is open to the air-passage o of the mouth-piece d, and to a series of vertically-inclined reed-chambers, t, 45 arranged in parallel lines and in vertical planes corresponding to the lines or rows of perforations in the music-strip, and to the vertical air-passage o of the mouth-piece d.

50 Each reed-chamber has a reed, d², arranged at a vertical inclination and in communication by an air-passage, w, with the outside, and by an air-passage, v, with the air-chamber or wind-chest S of the cap or case W; and each air-passage v has a separate valve, T, arranged 55 at an angle of inclination and hinged at its upper end, and all so as to be capable of opening from its own weight and of being closed against and over the air-passage. Each valve T has a bent spring, w, attached to it, and 60 through this spring it rests upon and against the upper arm, x, of an angular lever, U. These several angular levers preferably turn

in suitable guideways, y, of the cap or case W, and upon a common horizontal fulcrum-pin, z, and there is a lever for each valve and for each row of perforations in the music-sheet; and as to the music-sheet, each is arranged to bear by the tip a² at the outer end of its lower arm, b², down upon the unperforated parts of the music-strip and to pass into and project 70 through the perforations of the music-sheet into the air-passage o of the mouth-piece, according as either an unperforated or a perforated portion of the music-strip is passing under them, and this downward pressure of the 80 lever is because of its own weight and the weight of the valve, and its pressure because of the suction of air by the exhaust-bellows within the wind-chest or air-chamber S of the reed-board.

85 When a lever U is at rest upon an unperforated portion of the music-sheet, the valve connected to such lever, as has been described, is closed, and when it is in a perforation of the music-sheet said valve is opened, the latter 90 movement being allowable because of the release of the pressure of the lever on the spring of the valve, and the former movement being secured because of the then pressure of the lever upon the valve through its spring.

95 V is an opening at and along the rear side of the cap or case; and e² is a glass plate, properly secured in place and closing said opening.

In the mechanical musical instrument above described the music-strip as it passes through 100 the instrument is confined closely between the frame Q and the under side of the cap or case W, because the frame is free to move to such bearing from the pressure of air acting upon its outer and lower side in an upward direction, 105 and for the reason that the air is being exhausted in and out of the chamber S of the cap or case W by the operation of the bellows described; also, the spring w, making the connection between the valve T and the operating-lever U for the valve, and which receives its movement because of the passage of a perforated or unperforated part of the music-strip under its tip a², as has been described, secures elasticity in the pressure upon the valve to 110 close and hold it closed, and, also, can automatically adjust the valve to compensate for wear of the parts and unevenness of the music-strip. As each valve is suspended the instant the pressure of the operating-lever upon 115 it is released it is left free to open of its own weight, being assisted, of course, by the exhausting of the air through its reed or reed-chamber in a direction corresponding with the opening movement of the valve.

120 The mechanism composed of the reed-board R, with its reeds d² and reed-chambers t, valves T, and levers U for opening and closing the reed-chambers to the passage of air through them and their reeds, as has been described, 125 is all above the plane of movement of the music-strip, and is all contained upon and carried by the cap or case W, which board, as has been explained, it is preferred to secure in its place

so that it can be freely and readily placed in and out of position.

In Fig. 4 the reed-valve T is shown as located vertically upon the outside of the reed-board, 5 and to be opened by the movement or slide of a horizontal rod, f^2 , which is pressed forward against the valve by the swing of the lever U as it enters a perforation of the music-strip, and is withdrawn from the valve by the swing 10 of such lever U in the opposite direction because of the passage of an unperforated portion of the music-strip under the tip a^2 of the lever. The valve, when the lever is upon an unperforated portion of the music-strip, is 15 closed, and when the lever is within a perforation thereof is opened, the closing being caused by the pressure of air upon the outside and the suction of air upon the inside of the valve, and the opening by the pressure of the rod f^2 20 against the valve.

Fig. 5 shows the parts particularly described as to Fig. 4 in substantially a similar arrangement, and they differ from the same parts as arranged in Fig. 4 only in slight 25 details of construction, and in the valve T and its operating-rod f^2 being arranged at angles of inclination relative to the travel of the music-strip, all of which is apparent on an inspection of the two figures.

Fig. 6 is a view on an enlarged scale of a 30 reed-valve, and its construction and arrangement are in substance such as shown in Figs. 1, 2, and 3, and differ therefrom only in slight details, which are apparent on inspection— 35 as, for instance, in Fig. 6, the valve T in opening is limited by a headed stop-pin, g^2 , secured to the reed-board R, whereas in Figs. 1, 2, and 3 it is limited by a staple, h^2 , straddling the valve and fastened to the reed-board, provided of course in either case the operating- 40 lever U is not in position therefor.

If desired, springs l^2 , as shown, may be combined with the flexibly-connected board or frame Q to exert a yielding pressure thereon 45 in a direction to help to confine it against the music-strip and the strip against the reed-board.

The arrangement of the flexibly-connected and yielding frame Q herein described obviously operates independently of the mech- 50

anism controlling the reed-valves, and thus is capable of use when the music-strip constitutes of itself the valves to the reeds, it being of course only necessary that in such case each reed-chamber shall have a separate air-passage 55 leading from it to its line or row of perforations of the music-strip; or, in other words, that the open chamber S of the cap or case be constructed with separate air-passages leading to each reed-chamber from and in line with 60 the separate rows of perforations of the music-strip.

The several reed-chambers of the reed-board, at their upper portions, have a cover, m^2 , which is hinged at n^2 , and thus the reed-chambers can 65 be opened and closed to secure swell effects in the playing of the instrument.

Having thus described my invention, what I claim, and desire to secure by Letters Patent, is—

1. In a mechanical musical instrument, a cap or case carrying a reed-board having reed-chambers and reeds, valves to the reed-chambers, and mechanism for opening and closing said valves, which is arranged within and carried by said cap or case, in combination with a music-strip, P, bellows, and a suitable guide or race way for the music-strip, combined and arranged together, all substantially as described.

2. In a mechanical musical instrument, reed-chambers having reeds and valves, and levers U for operating said valves by a music-strip, P, in combination with bearing-springs between the levers and valves, all substantially 85 as and for the purpose described.

3. In a mechanical musical instrument, a reed-chamber having reeds and valves, and levers U for operating said valves by a music-strip, in combination with bearing-springs w 90 between the levers and valves, and attached to only one of the same, all substantially as described, for the purpose specified.

In testimony whereof I have hereunto set my hand in the presence of two subscribing witnesses.

OLIVER H. ARNO.
